UNITED STATES PATENT OFFICE.

FREDERICK DIETZ, OF NEW YORK, N. Y.

LANTERN-GLOBE SUPPORT.

SPECIFICATION forming part of Letters Patent No. 354,970, dated December 28, 1886.

Application filed July 21, 1885. Serial No. 172,228. (No model.)

To all whom it may concern:

Be it known that I, FREDERICK DIETZ, a citizen of the United States, and a resident of New York, in the county of New York and State of New York, have invented certain new and useful Improvements in Lantern-Globe Supports, of which the following is a specification.

My invention relates especially to devices employed for supporting the globe in "tubular" lanterns, and has for its object the provision of means whereby the perforated plate on which the globe rests is held against displacement or loss when the globe is removed from the lantern and the burner-cone is secured upon its seat.

To attain the desired end my invention consists, essentially, in a standard secured to the base of the lantern at one side of the air-chamber and burner-cone, to which the perforated globe-supporting plate is hinged, a spring connected with said hinge forcing the perforated or globe-supporting plate down upon its seat upon the burner-cone, all of which will be hereinafter first fully described, and then pointed out in the claim.

In the drawings, Figure 1 is a front elevation of a lantern whereon my improvement is employed; and Fig. 2 is a side elevation of a base of a lantern, showing the globe-supporting plate as tipped back.

Like letters of reference wherever they occur indicate corresponding parts in both figures.

A is the base of the lantern, B the air-chamber, C the burner-cone, and D the globe, constructed and arranged in the usual manner, the globe being held at top by the wire spring E.

F is the perforated plate upon which the globe is supported, said plate finding a seat upon the burner-cone.

G is a standard secured to base A, and H is a staple secured to or formed upon the under side of the perforated plate F. The standard and staple are united by a tube or its equivalent, I. Instead of securing the plate to the staple as shown, portions of the metal of the plate may be cut and bent therearound.

K is a spring engaging with the standard G and plate F in such a manner as to hold said plate firmly upon its seat, keeping the cone in place. When thus arranged, the globe may be tipped back for the purpose of lighting the lantern or reaching the burner, and the moment the globe is removed the spring will force the plate back upon the burner-cone, keeping the burner in place, preventing removal or loss of either plate, burner-cone, or burner.

I have made application of even date herein with (Serial No. 172,227) for a patent for an improvement in lantern-globe supports, and so far as the device shown and described therein is similar to my present application I make no claim herein; but,

Having now fully described my invention, what I claim as new therein, and desire to secure by Letters Patent, is—

The combination, with the lantern-base A and perforated plate F, of the standard G, staple H, tube I, and spring K, arranged substantially as shown and described.

Signed at New York, in the county of New York and State of New York, this 11th day of June, A. D. 1885.

FREDERICK DIETZ.
